FIG. 1

FIG. 2

FIG. 3

FIG. 4

FIGURE 1 is a perspective view of tumbler showing my new design;

FIGURE 2 is a side elevational view;

FIGURE 3 is an enlarged scale partial sectional view at the bottom thereof; and

FIGURE 4 is an enlarged scale partial sectional view at the top thereof.

The essential feature of my design resides in the combination on a tumbler of the configuration disclosed of a narrow ridge about the outer periphery of the lip and an annular stacking boss of substantially cylindrical form terminating at a point above the meeting line of the tapered upper portion and the cylindrical base portion substantially equal to the distance below such meeting line, as shown.

I claim:

The ornamental design for a tumbler, as shown and described.
